UNITED STATES PATENT OFFICE

167,882

LACE

Herbert Farnsworth, Norwalk, Conn., assignor to
I. Zendman, Inc., New York, N. Y.

Application May 17, 1952, Serial No. 19,768

Term of patent 3½ years

(Cl. D47—6)

To all whom it may concern:

Be it known that I, Herbert Farnsworth, a citizen of the United States of America, residing in Norwalk, county of Fairfield, and State of Connecticut, have invented a new, original, and ornamental Design for a Lace, of which the following is a specification, reference being had to the accompanying drawing, forming part thereof, wherein,

The figure is a plan view of a piece of lace showing my new design on a dark background, so as to bring out more clearly the details thereof, a unit of which is contained within the dot and dash lines.

I claim:

The ornamental design for a lace, substantially as shown and described.

HERBERT FARNSWORTH.
